(57) **CLAIM**

The ornamental design for pickup tool box, as shown and described.

DESCRIPTION

FIG. 1 is a front perspective view of a pickup tool box showing my new design;

FIG. 2 is a rear perspective view of the pickup tool box showing side pull-out trays; and,

FIG. 3 is a front elevational view of FIG. 1.

The broken line showing of environment is for illustrative purposes only and forms no part of the claimed design.
